UNITED STATES PATENT OFFICE

95,580

DESIGN FOR A COASTER WAGON

Joseph B. Eck, Sheboygan, Wis.

Application December 10, 1934, Serial No. 54,377

Term of patent 7 years

To all whom it may concern:

Be it known that I, Joseph B. Eck, a citizen of the United States, residing at Sheboygan, in the county of Sheboygan and State of Wisconsin, have invented a new, original, and ornamental Design for a Coaster Wagon, of which the following is a specification, reference being had to the accompanying drawing, forming part thereof.

In the drawing,
Fig. 2 is a fragmentary perspective view of the rear portion of the coaster wagon.

I claim:
The ornamental design for a coaster wagon, substantially as shown.

JOSEPH B. ECK.
